UNITED STATES PATENT OFFICE.

THOMAS MURPHY, OF MIDDLETOWN, CONNECTICUT, ASSIGNEE OF ONE-HALF TO
BERKLEY C. STONE, OF MIDDLETOWN, CONNECTICUT.

WRENCH.

Application filed May 15, 1923. Serial No. 639,076.

To all whom it may concern:

Be it known that I, THOMAS MURPHY, a citizen of the United States, residing at Middletown, in the county of Middlesex and State of Connecticut, have invented certain new and useful Improvements in Wrenches, of which the following is a specification, reference being had therein to the accompanying drawings.

This invention relates to a new and improved wrench and it is one of the objects thereof to produce a wrench that is adapted for use with objects of various sizes, the adjustment therefor being obtained quickly through manipulation of mechanism by the fingers of the hand holding the wrench and which will be locked against accidental movement in all of its adjusted positions.

Among other aims and objects of the invention may be recited the provision of a device of the character mentioned with a view to compactness and in which the number of parts are few, the construction simple, cost of production small but efficiency and operation high.

The improvements in the details and arrangement of parts will be apparent from an inspection of the accompanying drawings in connection with the description herein-after contained and wherein a preferred embodiment of the invention is disclosed for the purpose of imparting an understanding of the same.

In the drawings:—

Figure 1 is an elevation of my improved wrench showing the relative position of the hand in connection therewith while in operation;

Figure 2 is a plan view thereof;

Figure 3 is an enlarged fragmentary elevation thereof taken generally upon line 3—3 of Figure 2;

Figure 4 is an enlarged fragmentary elevation thereof taken generally upon line 4—4 of Figure 2;

Figure 5 is a view of the underside of one end of the lower jaw; and

Figure 6 is a plan view of the lock-plate.

In the drawings, wherein like characters of reference indicate corresponding parts in the several figures; 10 designates the upper jaw and 11 the lower jaw which are operatively connected at their rear ends by the pintle 12 and each provided upon an inner face near the outer end with teeth 13. One

of these jaws, preferably the upper jaw, is provided with a slot 14 substantially parallel to the length of the jaw, and the other jaw, preferably the lower jaw, with a slot 15 at an angle to its length and the outer face of the jaw adjacent to the slot 15 is provided with a plurality of notches 16.

Slidably mounted within the slot 14 is a non-rotatable collar 17, through which and the slot 15 projects a stud 18, the portion 19 thereof adjacent to the head of the stud being flattened on each side and projecting into the slot and held by the walls thereof against rotation.

Surrounding the flattened portion 19 of the stud adjacent to the head thereof, is a lock-plate 20 having teeth 21 upon one face which correspond in depth and relative location with the notches 16 with which they intermesh.

Threaded upon the shank 27 of the stud 18 is a knurled nut 22 which is cupped or recessed at its outer end 23 so that the thumb will more readily retain its contact therewith. The underside of the nut 22 is provided with a recess 24, into which projects a spring 25 which bears against a collar 26 surrounding the shank 27 and resting against the outer face of the jaw 10.

In operation, the wrench is grasped in the hand substantially as shown in Figure 1 and the toothed portions of the jaws placed in proximity to the article to be gripped by the wrench. These toothed portions are now moved toward and away from each other by applying a limited pressure with the thumb on the cupped end of the nut 22 and a slight endwise pressure applied thereto against the tension of the spring 25. During this movement the lock-plate 20 moves away from the lower jaw 11 and the teeth thereon are disengaged from the teeth 16. The stud 18 is then moved lengthwise within the slots 14 and 15 and by reason thereof the jaws are moved toward and away from each other, swinging upon the pintle 12. When the proper relative positions of the toothed portions 13 of the jaws are obtained, pressure upon the nut 22 is released, the spring 25 moves the stud endwise and the head of the stud 18 presses the teeth of the lock-plate into the teeth upon the lower jaw 11, thus locking the jaws against movement.

The nut 22 is located upon the stud 18 so

that in its down position its lower face will contact with the collar 26 and thus limit the movement of the stud and the lock-plate to a position wherein the teeth of the lock-plate will be entirely free from those on the jaw.

There are minor changes and alterations that may be made within my invention, aside from those herein suggested, and I would therefore have it understood that I do not limit myself to the exact construction herein shown, but claim all that falls fairly within the spirit and scope of the appended claims.

Having described my invention, what I claim as new and desire to secure by Letters Patent, is:—

1. In a wrench, a pair of members pivoted together adjacent one end and having jaws on their opposite ends, one of the members having an axial slot and the other an inclined slot which traverses the axial slot, teeth on the outer face of one of the members adjacent the slot thereof, a lock plate having a central slot with opposed parallel straight sides and having teeth for engagement with the first named teeth, a stud having a head on one end engaged with the lock plate and having flattened sides which engage with the parallel sides of the slot of the lock plate, a non-rotatable collar in the slot of the first

named member, the opposite end of the stud extending through the last named slot, a collar and a nut on said opposite end of the stud, and a coil spring between the last named collar and the nut, the outer face of the nut being cupped to form a thumb-receiving part.

2. In a wrench, a pair of members pivoted together adjacent one end and having jaws on their opposite ends substantially parallel with each other, one of the members having an axial slot and the other an inclined slot which traverses the axial slot, teeth on the outer face of one of the members adjacent the slot thereof, both of said slots being between the jaw portion of each of said members and their point of pivot connection, a lock element having teeth for engagement with the first named teeth and extending through the slots of said members, said element being slidable in the inclined slot but held against rotation, and depressible spring means for slidably and non-rotatably mounting said element and to hold same in position with its teeth always in register with the first named teeth whereby upon depression of said means the element will be released from the first named teeth.

In testimony whereof, I have hereunto affixed my signature.

THOMAS MURPHY.
